UNITED STATES PATENT OFFICE.

AUGUST IELFIELD, OF SILVER CREEK, NEW YORK, ASSIGNOR TO THE IELFIELD POSTAL SUPPLY CO. INC., OF FORESTVILLE, NEW YORK, A CORPORATION OF NEW YORK.

MAIL-MARKING MACHINE.

Application filed March 22, 1926. Serial No. 96,425.

This invention relates to a machine for marking mail matter such as letters, post-cards and the like which have to be taken care of in large quantities at times in the 5 postal service.

It is the object of this invention to provide improved registering and stopping means for controlling the operation of the printing wheel so as to produce but one impression of 10 the same at the proper place on each piece of mail matter; also to simplify and render more positive in action the rotation of the printing wheel when the same is released by the feeding of a piece of mail matter in position 15 to receive an impression or postmark; and also to provide improved means whereby the ink roller of the printing wheel may be easily and conveniently replenished with ink when required while the machine is running.

In the accompanying drawings:

Figure 1 is a top plan view of a mail marking machine embodying my improvements.

Figure 2 is a bottom plan view of the same. 25 Figure 3 is a fragmentary top plan view of the machine showing the inking mechanism with the cover of the ink fountain removed.

Figure 4 is a vertical section taken on line 4—4, Fig. 3.

Figure 5 is a vertical section taken on line 30 5—5, Fig. 3.

Figure 6 is a perspective view of the shifting lever forming part of the inking mechanism.

Figure 7 is a fragmentary horizontal section taken on line 7—7, Fig. 9, and showing the position of the parts of the stop and registering mechanism when no letter or piece of mail matter has been fed into position 40 to be marked.

Figure 8 is a similar view showing the position of the parts of the stop and registering mechanism after a letter has been marked but has not yet cleared the printing wheel.

Figure 9 is a fragmentary vertical longitudinal section taken on line 9—9, Fig. 8.

Figure 10 is a vertical section taken on line 10—10, Fig. 7.

Figure 11 is a perspective view of the friction or gripping block forming part of the friction clutch mechanism for coupling the printing wheel with the driving mechanism.

Figure 12 is a cross section taken on line 12—12, Fig. 8.

Similar characters of reference indicate 55 corresponding parts in the several figures of the drawings.

The numeral 20 represents the feed table having a supply portion 21 upon which the letters 23 or other mail matter to be marked 60 or canceled are stacked edgewise, and a receiving portion 24 upon which the mail matter is stacked after receiving the post mark or canceling stamp.

Arranged lengthwise above the feed table 65 is a guide wall having a rear section 25 against which the pile of uncanceled letters are pressed by a bar or follower 26, and a front section 27 from which the letters are successively pushed away by a stacking 70 wheel 28. The follower 26 is constantly moved toward the rear guide wall section 25 by an upright rock shaft 29 journaled in a bearing in the table and connected at its upper end with the presser bar or follower, a 75 rock arm 30 secured to the lower end of the presser rock shaft, and a spring 31 connecting said rock arm with the adjacent part of the feed table.

In front of the supply portion of the 80 table is arranged a transverse guide wall 32 which is separated at its inner end from the longitudinal guide wall section 25 by a separating passage 33 through which the letters move from the supply stack to the mechanism 85 which marks the letters and stacks the same.

The letters are fed away successively from the inner side of the supply stack by a feeding belt 34 which passes with its rear turn around a pulley 35 and its front turn around 90 a pulley 36 these pulleys being mounted on upright shafts 37, 38 carried by the feed table so that the operative stretch of this belt projects beyond the face of the rear wall section 25 and engages the letters of the supply stack 95 so as to move the same forwardly. Immediately in front of the passage 33 the letters are engaged on opposite sides by two separating wheels 39, 40 which continue the forward movement of the foremost letter but hold 100 back the succeeding letters of the supply stack.

Arranged lengthwise of the faces of the longitudinal guide wall sections and spanning the gap between the same is the operative stretch 41 of a carrying belt which passes with its rear turn around a pulley 42, its front turn around a pulley 43 and its return stretch 105

passes around a driving wheel 44. The latter is mounted on an upright shaft 45 journaled on the table and may be turned by a hand crank 46 or by power. The pulley 42 connects with the pulleys 36 and 40 and these pulleys turn in unison. The pulley 43 is preferably connected with the stacking wheel 28 and is mounted with the same on the feed table by a vertical pin 47.

- 10 In front of the separating wheels 39, 40 the carrying belt is engaged on its opposite sides by a pair of rear guide rollers 48, 49 and in rear of the stack section of the table the carrying belt is engaged on opposite sides 15 by a pair of front guide rollers 50, 51.

Between the front and rear pairs of guide rollers the letters or pieces of mail matter receive a postmark by the mechanism which contains my invention and which is constructed as follows:

The numeral 52 represents a printing wheel which is provided on its periphery with a die or type 53 adapted to engage with the letter and impress a cancelling or postmark thereon while this letter is supported on its opposite side by the carrying belt which latter at this point is supported on its back by a supporting roller 54. This printing wheel is driven frictionally by motion derived from the carrying belt and in this preferred organization is accomplished as follows:

The numeral 99 represents a driving wheel which engages its periphery with the lower part of the carrying belt 41, as shown in Fig. 10, so as to be rotated thereby. This driving wheel is provided with an upwardly projecting cylindrical hub 55 and turns on an upright pin 56 mounted on the feed table. The printing wheel rests at its lower end on the driving wheel and is provided with a central cylindrical bore 98 which receives the hub of the driving wheel and forms a pivotal connection between the same. Extending radially outwardly from the bore of the printing wheel is a longitudinal groove 22 in which is arranged a friction block 57 which turns with the printing wheel. This friction block is pressed inwardly so that its inner side bears against the periphery of the hub of the driving wheel. In its preferred form such pressure is produced by a bow leaf spring 100 bearing at its ends against shoulders 58 which are formed to face each other 50 at opposite ends of a recess 59 on the outer side of the friction block and bearing with its outwardly bulging central part against the bottom of the groove 22 in the printing wheel. When the latter is free the frictional grip of the block 57 against the hub of the driving wheel is sufficiently strong to compel these members to turn together and produce an impression of the type, die or printing surface of the printing wheel on the letter, card or other matter passing between

the carrying belt 41 and the periphery of the printing wheel.

The means whereby the rotation of the printing wheel is controlled in response to a letter which has been properly fed to the same for causing the printing wheel to effect a rotation for producing an impression on the letter are constructed as follows:

On its upper end and on one side of its axis the printing wheel is provided with an upwardly projecting pin forming a stop 60. Above the printing wheel is arranged a horizontal bracket or plate 61 which is supported on the feed table by posts 62 and provided adjacent to the face of the carrying belt with a guide bar 63 between which and this belt a guide-way is formed whereby the letters are directed from the supply stack to the printing mechanism. Pivoted by means of a bolt 64 or otherwise on the underside of the bracket 61 is a horizontal swinging stop lever of elbow or L-shape form and having a forwardly projecting longitudinal arm 65 and a laterally projecting arm 66. On its longitudinal arm the stop lever is provided with an anti-friction stop roller 67 which is adapted to move into and out of the path of the stop 60 on the printing wheel and thereby either arrest the rotation of the latter or permit rotation thereof with the driving wheel. The stop lever is yieldingly turned and held in a position in which its roller 67 stands in the path of the printing wheel stop by means of a spring 68 connecting this lever with the adjacent part of the bracket 61, and the movement of this lever under the action of this spring is limited by a stop 69 arranged on this bracket in position to be engaged by this lever, as shown in Figs. 7, 8 and 9.

Pivoted by a bolt 101 on the outer end of the transverse arm of the stop lever is a trip arm 70 which extends rearwardly from this pivot and is provided at its rear end with a hook shaped trip finger 71 which is adapted to project laterally across the path of the letters approaching the printing wheel or to be retracted therefrom. This finger is held in its operative or projected position so that it will cross the path of the letters by a spring 721 connecting the trip arm with the stop lever, and the movement of the trip arm under the action of this spring is limited by a stop face 72 on this lever engaging a stop face 73 on the arm.

Preparatory to moving a letter to the printing mechanism the stop lever is turned by its spring so that its stop roller stands in the path of the stop pin on the printing wheel and the latter is held against turning, and the trip arm is turned so that its finger projects across the letter path, as shown in Figs. 1 and 7. As a letter is moved forwardly from the supply stack by the feeding mechanism the front edge of the letter by engaging with the finger of the trip arm turns the

stop lever in the direction for moving its stop roller out of the path of the stop pin on the printing wheel. The instant this occurs the printing wheel is released and permitted to 5 turn forwardly by the friction clutch which couples the same with the driving wheel. During such rotation an impression of the face of the printing wheel is produced on the letter which at this time is moved forwardly 10 by the printing wheel and carrying belt engaging with opposite sides of the letter. At the end of one rotation of the printing wheel the same is arrested by the stop lever which after being deflected by the front end of a 15 letter again returns to its normal operative position in which the stop roller obstructs the path of the printing wheel stop pin 60. If at the end of one rotation of the printing wheel the letter has not yet cleared the printing 20 wheel then the trip arm and its finger upon engaging the side of the respective letter will be turned on the stop lever so as to remain on one side of the letter path, as shown in Fig. 8. The instant however that 25 the rear end of the respective letter passes forwardly beyond the trip finger the latter will be projected across the letter path ready to intercept the next following letter which upon engaging its front end with the trip 30 finger will cause the printing wheel to be unlocked and permitted to produce an impression on this letter in the manner previously described.

Means are provided for causing the printing 35 wheel to receive an impetus and to start its rotation the instant the same is unlocked by the proper presentation of a letter to the same by the letter feeding mechanism. These means preferably comprise a registering stop 40 consisting of an arm 74 projecting rearwardly from a pin or screw 75 which pivots the same on the upper end of the printing wheel and provided at its rear end with a laterally projecting registering finger 76 45 adapted to cross the letter path and to be engaged by the front end of a letter, a spring 77 connecting the registering arm with the printing wheel and tending constantly to turn the same in the direction for moving registering finger across the letter path, and a 50 stop 78 arranged on the printing wheel in position to be engaged by the registering arm and to limit its movement under the action of the spring 77. The instant that the printing wheel has been unlocked by the forward 55 pressure of the front edge of the letter against the trip finger of the trip lever then this letter engages its front edge with the finger of the registering stop and not only assists in starting the printing wheel but also causes the printing wheel to start at the proper time to imprint the canceling mark on the desired place on the letter. As the printing wheel rotates the registering stop is carried away 60 from the path of the letter and at the end of

the rotation of the printing wheel the finger of the registering stop is again carried across the letter path of the rear end of the letter has passed beyond. If however, the letter has not completely passed the printing position by the time the printing wheel has made one rotation then the registering stop upon engaging the side of the letter still present will be pushed backwardly over the printing wheel, as shown in Fig. 8, and held back 70 until the letter has cleared the registering stop finger and when this occurs the registering stop will be again turned by its spring so as to project its finger across the letter path 75 ready to intercept the next following letter 80 which is fed to the printing mechanism.

Although various means may be employed for inking the printing surface of the printing roll those shown in the drawings and embodying my invention are preferred and constructed as follows:

The numeral 79 represents an ink delivery roller which is pivotally mounted on the table or other available support and engages with the periphery of the printing wheel so that the same makes a legible impression on the letter to be marked. Adjacent to the outer side of this inking roller is arranged an ink fountain 80 which is arranged on a recess 81 in the table and provided with a lug 82 90 which is secured to the upper side of this table. The upper side of this fountain is closed by a cover 83 and detachably connected with the lug 82 by a screw 84 passing through a lug 85 on the cover. On its inner side the cover 83 is provided with an opening 86 which receives the outer part of the inking roller, as shown in Fig. 4. Arranged within the fountain and the cover is an ink feeding disk 87 which turns about a horizontal axis whereby its margin is caused to pick up ink contained in the fountain or reservoir and deposit the same on said inking wheel. During this operation the lower peripheral part of the inking disk sweeps through the ink supply and the inner side of its upper part engages with the inking roller and deposits the ink thereon. For the purpose of enabling the inking roller to be thus supplied with ink at will when required means are provided for 100 moving the inking disk axially into and out of engagement with the periphery of the inking roller. This is preferably accomplished by rotatably mounting the inking disk on a shaft or arbor 88 which is supported on the upper part of the fountain so that the inking disk can slide lengthwise thereon, this sliding motion being preferably effected by a hub 89 arranged on the inking disk and provided with an annular groove 90, and a shifting lever 91 provided with a fork 92 engaging with the groove of this hub. This lever has one end pivoted in recess 93 at one end of the fountain and its other end passes through 105 a horizontal slot 94 in the cover and provided 110

120

125

130

externally thereof with a handle 95 for manipulating the same. When free the inking disk is yieldingly held in engagement with the periphery of the inking roller by a spring 96 surrounding the shaft 88 and interposed between the hub 89 and the adjacent wall of the fountain, as shown in Figs. 3 and 4. When in this position the inking disk is turned by frictional contact with the inking roller so that ink is constantly lifted from the fountain to the inking roller. Upon moving the inking disk away from the inking roller by means of the shifting roller the rotation of the inking disk and its feeding action ceases. The inking roller is held out of engagement from the inking disk by engaging the outer arm of the shifting lever with a hold out shoulder 97 formed on the upper edge of the ink fountain which forms the lower side of the slot 94.

This inking mechanism permits of very conveniently and thoroughly supplying ink to the roller which inks this printing wheel, thereby enabling the postmarking to be effected uniformly and economically.

I claim as my invention:

1. A mail marking machine comprising a printing wheel provided with a stop, a unitary stop member movably mounted on a stationary support and provided with a stop movable into and out of the path of the stop on said wheel and a trip member movably mounted on said stop member and adapted to be engaged by the mail matter to be marked.

2. A mail marking machine comprising a printing wheel provided with a stop, a unitary stop lever pivoted on a stationary support and provided with a stop movable into and out of the path of the stop on said wheel, and a trip arm pivoted on said stop lever and adapted to be engaged by the mail matter to be marked.

3. A mail marking machine comprising a printing wheel provided with a stop pin, an L-shaped stop lever pivoted on a stationary support and having a laterally projecting arm and a forwardly projecting arm provided with a stop roller movable into and out of the path of said stop pin, and a trip arm pivoted on said laterally projecting arm and having a finger adapted to be engaged by the mail matter to be marked.

4. A mail marking machine comprising a printing wheel provided with a stop, a stop lever pivoted on a stationary support and provided with a stop movable into and out of the path of the stop on said wheel, a trip arm pivoted on said stop lever and adapted to be engaged by the mail matter to be marked, yielding means for turning the stop lever and holding its stop in the path of the printing wheel stop, and yielding means for turning said arm and holding the same in the path of the mail matter.

5. A mail marking machine comprising a

printing wheel providing with a stop pin, an L-shaped stop lever pivoted on a stationary support and having a laterally projecting arm and a forwardly projecting arm provided with a stop roller movable into and out of the path of said stop pin, a trip arm pivoted on said laterally projecting arm and having a finger adapted to be engaged by the mail matter to be marked, a spring connecting said lever and support and turning this lever in the direction for moving its stop roller into the path of said stop pin, means for limiting the movement of said lever under the action of said spring, a spring connecting said arm and lever and turning said arm in the direction for moving its finger into the path of the mail matter, and means for limiting the movement of the trip arm under the action of the spring connecting the same with the stop lever.

6. A mail marking machine comprising a printing wheel provided with a stop, a unitary stop member movably mounted on a stationary support and provided with a stop movable into and out of the path of the stop on said wheel, a trip member movably mounted on said stop member and adapted to be engaged by the mail matter to be marked, and a registering stop movably mounted on said printing wheel and adapted to be engaged by the mail matter to be marked.

7. A mail marking machine comprising a printing wheel provided with a stop, a stop member movably mounted on a stationary support and provided with a stop movable into and out of the path of the stop on said wheel, a trip member movably mounted on said stop member and adapted to be engaged by the mail matter to be marked, a longitudinally registering stop arm pivoted on the printing wheel and provided at its rear end with a finger adapted to project laterally across the path of the mail matter, a spring connecting the registering stop arm with said wheel and tending constantly to hold said finger in the path of the mail matter, and means for limiting the movement of said finger on said stop arm under the action of the spring connecting the same.

8. A mail marking machine comprising a printing wheel provided with an axial cylindrical bore and a longitudinal groove extending radially outward from said bore, a driving wheel having a cylindrical hub engaging with the cylindrical bore of said wheel, a friction block arranged in said groove and bearing with its inner side against the periphery of said hub and provided on its outer side with a recess forming two shoulders which face toward each other, and a bow leaf spring engaging its ends with said shoulders and its central part with the bottom of said groove.

In testimony whereof I affix my signature,
AUGUST IELFIELD.
